HORACE P. TUTTLE, OF BROOKLYN, NEW YORK.

Letters Patent No. 100,821, dated March 15, 1870.

IMPROVEMENT IN HAND INDICATOR FOR SHOWING THE COURSE OF VESSELS.

The Schedule referred to in these Letters Patent and making part of the same

To all whom it may concern:

Be it known that I, HORACE P. TUTTLE, of Brooklyn, in the county of Kings, and State of New York, have invented a new and improved Course-Indicator for Vessels; and I do hereby declare that the following is a full, clear, and exact description thereof, which will enable others skilled in the art to make and use the same, reference being had to the accompanying drawings forming part of this specification.

Figure 1 represents a plan or top view of my improved course-indicator.

Figure 2 is a vertical section of the same.

Similar letters of reference indicate corresponding parts.

This invention relates to a new instrument by which the true course of a vessel, with regard to the variations of the needle, can be readily ascertained.

The invention consists in the combination of two pointers turning on the same pin. They are so ground and held together that they will both move simultaneously, so that when one is set the other will also move, unless held fast.

A, in the drawing, represents a dial-plate, on which the several points of the compass are marked.

In its center is arranged a projecting pin, *a*, upon which two hands or pointers, *B C*, are fitted, they being held down by a screw, *b*.

Their contiguous surfaces, immediately around the pin *a*, are ground together, and the pressure upon them by the screw is sufficient to cause them to move together.

The device is used as follows:

The upper hand *C* is set on the dial-plate, to indicate the course, according to compass, of the vessel,

giving the requisite margin for any displacement by wind, currents, &c. The lower hand *B* is then placed over zero, to point toward north. The two hands were moved separately to the two positions shown in the drawing, and the one not moved was held fast, while the other was set. Now, in order to find the actual course, the hand *B* is shifted as far toward east or west as the needle of the compass may vary at the place where the ship is situated. By such motion the hand *C* will also be carried in the same direction, and will then indicate the proper direction, according to the needle.

Thus, if a ship should steer ESE., with a strong easterly wind causing it to go SE. in a place where the needle varies two degrees toward W., the true course will be two degrees S. of SE.

By this device the mistakes frequently made by captains, in trying to find the true course, are overcome. When a ship steers in a southerly direction, men will often calculate the course to be more toward west, when the needle varies toward the west, while such variation shows a difference of the course toward east.

Having thus described my invention, I claim as new and desire to secure by Letters Patent—

A course-indicator, consisting of a dial-plate having the several points of the compass marked thereon, projecting pin *a*, pointers *B C*, and screw *b*, all adjusted and operated as set forth, and for the purpose specified.

H. P. TUTTLE.
